UNITED STATES PATENT OFFICE.

EDWARD C. ABT, OF CHICAGO, ILLINOIS.

RADIATOR COVER.

Application filed November 7, 1923. Serial No. 673,337.

This invention relates to radiator covers for motor vehicles, such as automobiles, trucks and the like, and its principal object is to provide a cover with a movable shield and capable of being readily attached to the radiator or its enclosing shell in front of the radiator to protect it against the direct entrance of cold air, or rain, snow and sleet, in any of its various positions of adjustment. 5 Another object is to furnish a radiator cover with a movable shield that extends across the space in front of the radiator of motor vehicles and capable of being adjusted to various positions in front of the radiator, 10 whereby the direct entrance of air to the core is prevented, but entrance is effected in lateral directions between the shield and radiator. It is well known that the direct entrance of cold air, rain, sleet and snow 15 through the radiator core is injurious to vulnerable parts contained under the hood, and that less efficiency is obtained when the motor is cold. It is also well known that with 20 water or air cooled motors, a circulation of air is necessary to prevent overheating. With the present device, the temperature under the hood of the motor vehicle may be regulated at will, without exposing the parts under 25 the hood to the inclemencies of the weather. 30 Another object of the invention is to provide a radiator cover which may be applied to the common and well known fabric radiator covers, as a part of said cover, or as a separate device, capable of being readily attached to the ordinary fabric radiator cover, 35 to convert it into a device embodying one form of the present invention.

To such ends this invention consists in a movable shield arranged to be supported in front of and contiguous with the radiator front of motor vehicles, and having means whereby it may be moved forward to leave lateral openings and a free passage way between it and the radiator front. It further 40 consists in the provision of brackets for supporting the shield in position in front of the radiator and in various positions of adjustment in front of the radiator. It further 45 consists in the several novel features hereinafter 50 fully set forth and claimed. The invention is clearly illustrated in the drawings accompanying the specification, in which:

Fig. 1 is a front elevation of a radiator

cover embodying one form of the present invention, and showing the same applied to the 55 radiator of a motor vehicle; Fig. 2 is a vertical cross section thereof, taken on line 2—2 of Fig. 1; Fig. 3 is a horizontal section taken on line 3—3 of Fig. 1; Fig. 4 is a side elevation illustrating a dash control mechanism 60 for operating the device; Fig. 5 is a front elevation of a modified form of the invention; Fig. 6 is a vertical cross section taken on line 6—6 of Figure 5, and Fig. 7 is a horizontal section taken on line 7—7 of Figure 5. 65

Referring to said drawings, and first to Figs. 1 to 4, inclusive, which show the application of one form of the invention to a metal radiator cover, the reference character 11 designates a radiator, of the type usually employed in motor vehicles, such as automobiles, trucks and the like, and 12 designates the core of the radiator. Secured to or forming a part of the front of the radiator, is a cover plate 13, which may conform generally to the 70 shape of the radiator front, and said cover plate has one or more openings 14, through which air is admitted to and through the radiator to the parts beneath the hood (not shown), for the purpose of cooling the motor. In cases where more than one opening 75 14 is used, they are separated by strips 15, formed upon the cover plate 13. The strips 15 are set forward of the front face of the radiator core so as to permit air to pass 80 around and behind said strips and into the air passages in the radiator core. The cover plate may be secured to the radiator by 85 bolts 12^a.

In front of said opening in the cover plate, 90 is a shield or cover 16, which is of sufficient size to completely cover the opening or openings 14 in the cover plate, to thereby prevent the direct entrance of air, or rain, snow and sleet, to and through the radiator core. Said 95 shield 16 is movably mounted on the cover plate 13 and is capable of being adjusted forwards and backwards to provide a passage way between the radiator and shield, having an inlet opening at the sides and bottom. 100

In the form of the invention illustrated in Figs. 1 to 4, inclusive, the shield is made in two sections 16^a, 16^b, hingedly connected together at 17. The section 16^b is relatively narrow and spaces the upper end of the section 16^a from the cover plate 13, when the 105

shield is moved forward. The shield is hingedly connected at its upper end to the cover plate by a hinge connection 18, whereby the section 16^b may be swung up or down to move the section 16^a away from or toward the cover plate. The drawing shows the shield in its fully open position.

Means are provided whereby the shield may be manipulated from the front of the 10 radiator or from the dash or instrument board of the vehicle, and in the form shown in Figs. 1 to 4, inclusive, crank arms or links 19, 20, connect the shield with the cover plate, and one of said crank arms is formed 15 with a crank arm 21 which may be connected to an actuating wire or rod 22 which runs to the dash or instrument board 23, where it is provided with a handle 24 by which it may be manipulated. Any suitable means may be 20 provided for releasably holding the arm 19 and therewith the shield, in any position of adjustment, and as shown the handle 24 may have teeth for this purpose, that engage with a plate or catch on the dash or instrument 25 board. The crank arms are hingedly connected to the cover plate and to the shield and the upper ones 19 are arranged parallel with the lower ones 20. The crank arms are rotatively mounted on the cover plate and as shown, their ends 19^a, 20^a extend through 30 a marginal L-shaped flange 16^c which is struck up from the cover plate at the opening or openings 14. The other ends of the crank arms 19 are shown as held between the 35 section 16^c of the shield and metal strips 26, secured to the under or inner side of the section 16^b. The lower crank arms are secured to the shield by hinge plates 27. By properly manipulating the rod or wire 22 the shield is moved toward or away from the 40 cover plate to decrease or increase the air inlet openings at the sides and bottom of the shield.

If desired, the shield may have one or more 45 slots 28 formed therein, in front of the division strip or strips 15 of the cover plate, and the side edges of the shield may be formed with flanges or beads 29 that overlap the flanged or offset part of the cover plate when 50 the shield is fully closed.

In the modified form illustrated in Figs. 5, 6 and 7, the shield 16^s is shown as secured at its upper edge to a radiator cover 13^s, and arranged to cover the opening 14^s therein. The 55 ordinary snap fasteners may be provided for securing it in its open and closed position. In this case the shield is held in distended position by brackets 33 supported in any suitable manner, as for instance by the cover 13^s itself. The lower end of the shield may be detachably secured to the lower bracket by snap fasteners 8, when distended, and to the cover 13^s by snap fastener members 8¹ on the cover, that co-act with those on the shield.

65 From the above, it is obvious that the in-

vention may be embodied in a radiator cover, as a part of the radiator, or it may be embodied in a metal or fabric radiator cover, capable of being readily secured to the radiator. By preventing direct entrance of cold air, rain, sleet or snow through the radiator core, the temperature of the parts under the hood may be regulated with greater certainty, thereby insuring a maximum efficiency of operation of the motor, and the 70 other devices under the hood are not exposed to rain, sleet or snow as in the case where the radiator cover is exposed directly to the cold air, rain, snow and sleet.

More or less variation of the exact details 80 of construction is possible without departing from the spirit of this invention; I desire, therefore, not to limit myself to the exact form of the construction shown and described, but intend in the following claims, 85 to point out all of the invention disclosed herein.

I claim as new and desire to secure by Letters Patent:

1. In a cover for radiators having a core 90 and an enclosing shell provided with an opening in front of the core, a movable shield arranged to extend across said opening in the shell, hinged arms connected to said shield adjacent two opposite edges thereof, and means for holding one of said arms in any position of adjustment thereof, whereby said shield may be held in various positions approximately parallel with said enclosing shell.

2. In a cover for radiators having a core and an enclosing shell provided with an opening in front of the core, a cover member secured upon said radiator, and having an 105 opening in front of said core, a shield, arranged to extend across said opening, upper and lower arms hingedly connected to said cover member and to said shield, and means for securing one of said arms in any position of adjustment thereof.

3. In a cover for radiators having a core and an enclosing shell provided with an opening in front of the core, a cover member secured upon said radiator, and having an 110 opening in front of said core, a shield arranged to extend across said opening, and movable toward and away from said opening, and means for securing said shield in any position of adjustment thereof, including arms hingedly secured to said cover member and 115 to said shield.

4. In a cover for radiators having a core and an enclosing shell provided with an opening in front of the core, a cover member secured upon said radiator, and having an 120 opening in front of said core, a hinged together, two piece shield arranged to extend across said opening, and having one part secured to said cover member above said opening, said shield being movable toward and 125

away from said opening and means for securing said shield in any position of adjustment thereof.

5. A cover for radiators, comprising a shield covering the core of the opening of the radiator, and parallel movement means to support said shield so as to resist direct entrance of air to the radiator in a direction at right angles to the plane of the shield, and in all positions of adjustment of the shield, there being a laterally opening, unobstructed space directly behind said shield, and said shield being adjusted outwardly on parallel lines to leave side ventilating openings.

15 6. A cover for radiators, comprising a shield, and parallel movement means for holding said shield constantly parallel with the radiator, and there being a laterally opening, unobstructed space directly behind said shield, said shield being adjustable on parallel lines toward and away from the radiator core to leave side ventilating openings in all open positions of the shield.

25 7. A cover for radiators comprising a two part hinged together shield arranged to cover the radiator core, one part of said shield being movable toward and away from the radiator to leave side ventilating openings, and said shield being adapted to resist direct entrance of outside elements.

35 8. A cover for radiators, comprising a shield covering the outside of the air cooling portion of the radiator and parallel movement means supported by said shield, there being a laterally opening, unobstructed space directly behind said shield, and said shield being adjustable toward and away from the radiator to leave side ventilating openings and to resist direct entrance of outside ele-

ments, in a direction at right angles to the 40 plane of the shield, and in all positions of adjustment of the shield.

9. A cover for radiators, comprising a plate arranged to be secured on a radiator and having spaced apart openings for exposing 45 the radiator core, and a shield having solid parts constantly and entirely covering said openings in the plate, and having an opening in front of the solid place between said openings of the plate, the solid parts of the plate and shield constantly overlapping the edges of the openings, and said shield being hinged- 50 ly connected to the plate at two opposite ends by parallel movement means and capable of being spaced away from said plate to leave 55 side ventilating openings.

10. A cover for radiators, comprising a shield located in front of the radiator and operating to resist direct entrance of air to the 60 radiator in a direction at right angles to the plane of the shield and in all positions of adjustment, there being a laterally opening, unobstructed space directly behind said shield, said shield being movable away from said 65 radiator on parallel movement means to afford side ventilating openings.

11. A cover for radiators comprising a two part hinged together shield located in front of the radiator, and acting constantly to resist direct entrance of air to the radiator, 70 one of said parts being fulcrumed on a support on the radiator, and a swinging arm hingedly connecting one end of the shield with said support, said shield being movable toward and away from the radiator, whereby 75 side ventilating openings are provided when the shield is moved away from the radiator.

EDWARD C. ABT.
